UNITED STATES PATENT OFFICE.

WILLIAM W. HOSFORD, OF NEW BRITAIN, CONNECTICUT.

IMPROVEMENT IN SASH-FASTENINGS.

Specification forming part of Letters Patent No. 55,298, dated June 5, 1866.

To all whom it may concern:

Be it known that I, WILLIAM W. HOSFORD, of New Britain, county of Hartford, and State of Connecticut, have invented certain new and useful Improvements in Sash Supports or Fasteners; and I do hereby declare that the same is described and represented in the following specification and drawings, so as to enable others skilled in the art to make and use the same.

I will therefore proceed to describe by referring to the drawings, in which the same letters of reference refer to like parts in each of the figures.

The nature of this improvement will be understood from the specification and drawings.

The object desired to be attained thereby is to produce a cheap, simple, and efficient article, which shall be tasteful in its appearance, cheap and labor-saving in preparing for market, effective and desirable for fastening or holding the sash in position, and not liable to get out of order.

In the accompanying drawings, Figure 1 is a face view, represented as being secured upon the stile of a sash or upon the jamb of a window. Fig. 2 is a sectional view. Fig. 3 is an under-side view of eccentric cam *e*, having an arm or lever, *o*, for turning the cam in the desired direction. Fig. 4 is a face-plate, to or upon which the cam is secured, and by which the whole fastener is secured to the sash or jamb.

The face-plate *a* is made of any desirable shape and configuration, having lugs *b* formed on the under or back side, which are designed to be let into the wood to hold the plate in its proper position, so that (with the aid of screws in the common way) they shall be held firmly to the jamb or sash. Upon the face side of this plate is provided a hub, *c*, into which is fitted the screw *d*, which serves as a fulcrum for the cam *e* to play upon and to hold it firmly to the plate *a*.

h are protuberances formed on the face side of the plate *a*, having depressions which form

seats, in or upon which the ends of the spring *i* take its bearing, and is held therein by the arm *o*. The spring *i* is formed with a prominence, *i'*, near its center, the object of which is to enter the depression *i''* in the cam *k*, to hold the cam *e* in an inactive or locked position when not wanted for holding or fastening the window.

The pin or screw holes of the cam *e* are made eccentric with the outside surface or bearing-surface thereof, so that as the cam is turned by means of the arm or lever *o* in either direction it will bind against the jamb or sash, and thus hold the window in either a raised or closed position.

Thus it will be seen that by the use of this improvement the window may be raised or lowered freely without hinderance from the fastening until it said is required, and when raised or lowered it will be held firmly by simply turning the arm *o* so as to bring the cam *e* into action. That is, when the sash is raised, by turning the lever or arm *o* up it will bring the face-surface of the cam *e* against the jamb or sash, when the harder the pressure the tighter it will hold. So, when the window is closed, by turning lever or arm *o* in the opposite direction, the window will be fastened.

This improvement is susceptible of various modifications in its size and style without changing the principle of its operation. I believe I have thus shown the nature, construction, and operation of this my improvement, so as to enable others skilled to make and use the same therefrom.

What I claim, therefore, and desire to secure by Letters Patent, is—

The combination of the cams *k* *e* with the plate *a*, spring *i*, and arm *o*, arranged and operating substantially as and for the purpose described.

WM. W. HOSFORD.
